ROOF STRUCTURE

Johannes C. P. Leemhuis, Los Angeles, Calif.

Application February 27, 1939, Serial No. 258,633

10 Claims. (Cl. 108—10)

This invention relates to a structure for roofs. More particularly it relates to a structure formed by the aid of a series of overlapping precast plates, somewhat in the nature of shingles or tile.

It is one of the objects of this invention to make it possible to provide a roof structure that is inexpensive and that may be readily assembled.

For this purpose, the plates are preferably made from reinforced concrete. Furthermore, in order to make it possible to use plates of very simple construction, these plates overlap only in the direction of the roof slope. Moisture is thus drained downwardly, but the overlap does not prevent the moisture from entering between the adjacent side edges of the plates. It is another object of this invention to ensure that the moisture that may thus pass between the plates, is drained off to the edges of the roof. For this purpose the plates are arranged to be supported on spaced rafters, the top edges of which are provided with channel-like drains.

It is still another object of this invention to provide a roof plate of simple structure that can be readily utilized in a roof structure of the character set forth hereinbefore.

This invention possesses many other advantages, and has other objects which may be made more easily apparent from a consideration of several embodiments of the invention. For this purpose there are shown a few forms in the drawings accompanying and forming part of the present specification. These forms, which illustrate the general principles of the invention, will now be described in detail; but it is to be understood that this detailed description is not to be taken in a limiting sense, since the scope of the invention is best defined by the appended claims.

Referring to the drawings:

Figure 1 is a fragmentary sectional view, taken along plane 1—1 of Fig. 3, and illustrating a portion of the roof structure, and the manner in which the roof plates may be assembled;

Fig. 2 is a sectional view similar to Fig. 1, but taken along plane 2—2 of Fig. 3;

Figs. 3, 4, 5 and 6 are respectively sectional views taken along correspondingly numbered planes of Fig. 1;

Fig. 7 is a bottom view of one of the roof plates;

Fig. 8 is a fragmentary enlarged sectional view of a modified form of the invention;

Fig. 9 is a plan view, partly broken away, of a roof incorporating the invention;

Fig. 10 is detail pictorial view, partly in section, illustrating the manner in which a gutter may be supported at the eaves of the roof;

Fig. 11 is a pictorial view, partly in section, illustrating the manner in which the ridge of the roof structure may be constructed;

Fig. 12 is a sectional view similar to Fig. 4 but of a still further modified form of the invention; 5

Fig. 13 is a fragmentary sectional view adjacent the eaves of the roof, illustrating one manner in which the lowermost roof plates may be restrained against downward movement. 10

The roof plates 1 shown in all the figures are of general rectangular configuration. They are illustrated in the present instance as formed of concrete or other plastic material as by the aid of casting. The main body portion presents an exterior flat surface which is intended to form the exposed roof surface. Adjacent each side of the body portion are respectively the side flanges 2 and 3. Each roof plate is furthermore provided with a forwardly extending portion or extension 4 (Figs. 1, 2, 7, 10 and 13). The flanges 2 and 3, although they extend to the rear edge 5 of the roof plate, do not extend beneath the extension 4. As illustrated most clearly in Figs. 1 and 2, the extensions 4 overlap the rear edges 5 of the next 20 adjacent roof plate to provide a shingle effect. 15

In order further to strengthen the structure as well as to provide a means for anchoring adjacent roof plates together, the roof plates are each provided with downwardly directed portions adjacent the front and rear edge. Thus at the rear there is a flange-like downwardly directed member 6 and there is a correspondingly downwardly directed member 7 adjacent the front edge of the plate. These flanges are shown to best 30 advantage in Figs. 3, 4 and 7. A transverse rib 8 extends centrally of the roof plate 1 at its under side. Extending on each side of the rib 8 are a number of oblique ribs such as 9, 10, 11 and 12. There is a continuation 13 of the rib 8 between the front downwardly extended portion and the ribs 11 and 12. 35

In order to anchor the adjacent plates together, each rear extension 6 of the plate is provided with an aperture 14 which extends into the central rib 8. A corresponding through aperture 15 is provided through the front downwardly extended portion 7. Anchor pins 16 are shown as passing through these apertures. 40

If desired, the lower edges of the flanges 2 and 3 and the extensions 6 and 7 may be grooved as indicated for example at 17 (Fig. 2). A similar groove 18 is indicated on the bottom of the extension 4. At the top rear edge 5 a similar 50

groove 19 is also shown. These grooves provide adequate drainage provisions.

The manner in which the series of roof plates may be supported on roof rafters may be best explained in connection with Figs. 1 to 6, inclusive. Rafters 20, shown in this form as of wood, may be spaced apart corresponding to the width of a plate 1, as shown most clearly in Figs. 3, 4, 5 and 6. On the top of each of these rafters there is located a trough support 21, as of sheet metal. This trough support is wide enough so that the bottoms of the flanges 2 and 3 of adjacent plates may rest therein. A slight clearance such as indicated at 22 in Fig. 3 may be provided between adjacent flanges 2 and 3 of adjacent plates. The trough 21, however, acts to drain off any moisture which may flow through the clearance openings 22. These clearance openings 22 as shown most clearly in Fig. 9 extend longitudinally of the rafters. Transverse to the rafters, of course, the overlapping extensions 4 prevent moisture from entering underneath the plates. The ribs 8, 9, 10, 11, 12 and 13, in addition to their serving as strengthening ribs, also provide guides for condensed moisture to flow centrally and downwardly toward the front downwardly extending portions 7.

The manner in which the ribs and grooves operate to drain moisture of condensation that may form on the various surfaces may be briefly outlined. The groove 19, for example, adjacent the back of the plate 1, guides the moisture to the troughs 21. It further ensures against the retention of any moisture by capillary attraction between the overhanging extension 4 and the back edge of the lower plate. Similarly, rib 8 serves to guide the moisture downwardly to transverse ribs 11 and 12; these in turn guide the moisture to the side flanges 2 and 3 and into the troughs. Ribs 9 and 10 serve as guides for the moisture onto central rib 8. Rib 13 starts at a higher level (Figs. 1 and 7) and breaks the flow downward and spreads it to the side flanges 2 and 3, and thence into the troughs. Groove 18 may be utilized for caulking.

The flanges 2 and 3, however, do not rest along their entire bottom edges upon the bottom of the trough 21. As shown most clearly in Figs. 1 and 2, the front portion of the flanges 2 and 3 slope slightly upwardly as indicated by the line 23. In this way, the flow of moisture into the troughs 21 is unimpeded. In addition, the front and rear projections 7 and 6 respectively are arranged to rest upon the top edges of the troughs 21. This is indicated in Figs. 3 and 4.

In order to tie the plates 1 to the rafters 2, binding wire such as indicated at 24 in Figs. 2, 3 and 4, may be utilized. These binding wires may extend around the rafters 20 and through appropriately formed apertures in the rear extensions 6. As shown most clearly in Fig. 3, one continuous binding wire may pass through both rear extensions 6 of adjacent plates 1.

In order further to restrain the series of roof plates from sliding downward on the sloping rafters 20, appropriate provisions therefor may be made as indicated in Fig. 13, adjacent the eaves of the structure. In this figure the trough 21 is shown as being provided with projections 25 adapted to engage the front downwardly extending portion 7 of the lowermost plate 1.

A gutter arrangement may also be provided by the aid of brackets 26 interposed between the bottom of the gutter 21 and the rafter 20. Upon these brackets may be disposed the gutter 27.

The gutter 27 may be supported in other ways. For example, in the form shown in Fig. 10, the gutter brackets 28 may be supported at intervals on each downward extension 7 along the eaves, as by the aid of bolts 29.

At the ridge of the roof the rear downwardly extending projections 6 form a narrow pocket as illustrated in Fig. 11. In order to cover this pocket and to prevent the ingress of moisture, ordinary tile 3 may be placed in overlapped relation as a coping over this space and held in place for example by grouting 31. In valleys conventional metal flashing may be used.

It is not essential to utilize wood rafters. In the form of the invention shown in Fig. 8 the rafter structure is provided by a concrete beam 32 appropriately reinforced as indicated at 33. In this enlarged figure there are also indicated the reinforcing elements 34 which may, if desired, be utilized within the plate 1. It is possible in this form so to shape the top edge of the rafter structure 32 as to provide a trough 35 within which the flanges 2 and 3 of adjacent plates may be accommodated.

In the form of the invention illustrated in Fig. 12, the rafter 36 may be made from structural metal somewhat in the nature of an I-beam. Its upper edge may be formed into a trough 37 for the accommodation of the adjacent flanges 2 and 3 of the plates 1.

What is claimed is:

1. In a roof plate, a body portion, flanges along one pair of opposite sides, an overhanging extension for the body portion transverse to the flanges, downwardly extending portions respectively adjacent the front and rear edges of the body portion, one of said portions being to the rear of said extension, there being an aperture in each of said downwardly extending portions for accommodation of anchoring pins between the downwardly extending portions of adjacent plates, and a moisture collecting rib extending between said downwardly extending portions.

2. In a roof structure adapted to be utilized in connection with spaced supporting rafters or beams, a trough supported on each of the beams, a series of overlapping plates having side flanges extending into said troughs, and extensions carried near the top and bottom edges of the plate and having lower edges adapted to rest on the upper edges of the trough, and a moisture collecting rib extending between said downwardly extending portions.

3. In a roof structure adapted to be utilized in connection with spaced supporting rafters or beams, a trough supported on each of the beams, a series of overlapping plates having side flanges extending into said troughs, extensions carried near the top and bottom edges of the plate and having lower edges adapted to rest on the upper edges of the trough, and means cooperating with the lowermost plates for restraining them from downward movement.

4. In a roof structure adapted to be utilized in connection with spaced supporting rafters or beams, a trough supported on each of the beams, a series of overlapping plates having side flanges extending into said troughs, extensions carried near the top and bottom edges of the plate and having lower edges adapted to rest on the upper edges of the trough, and anchor members carried at the ends of the troughs and adapted to cooperate with the extensions of the lowermost plates for restraining downward movement of the plates.

5. In a roof plate, a body portion, flanges respectively adjacent the side edges of the body

portion, a downwardly extending portion adjacent the front edge of the body portion, said side flanges meeting said downwardly extending portion, and a moisture guiding rib on the lower surface of the plate, and extending from the rear toward the downwardly extending portion. 5

6. In a roof plate, a body portion, flanges respectively adjacent the side edges of the body portion, a downwardly extending portion adjacent the front edge of the body portion, said side flanges meeting said downwardly extending portion, a moisture guiding rib on the lower surface of the plate, and extending from the rear toward the downwardly extending portion, and 10 transverse ribs joined to the said moisture guiding rib and respectively extending substantially to the side flanges. 15

7. In a roof plate, a body portion, flanges respectively adjacent the side edges of the body portion, a downwardly extending portion adjacent the front edge of the body portion, said side flanges meeting said downwardly extending portion, a moisture guiding rib on the lower surface of the plate, and extending from the rear toward the downwardly extending portion, transverse ribs joined to the said moisture guiding rib and 20 respectively extending substantially to the side flanges, and supplemental transverse ribs also joined to said moisture guiding rib. 25

8. In a roof plate, a body portion, flanges respectively adjacent the side edges of the body portion, a downwardly extending portion adjacent the front edge of the body, and a series of ribs for guiding moisture to the side flanges, including 30 a rib on the lower surface of the plate, and ex- 35

tending from the rear to near the downwardly extending portion, and substantially central of the plate, a pair of transverse ribs extending from near the front end of the said central rib to the side flanges, a supplemental pair of transverse ribs joining an intermediate point of the central rib, and a continuation of the central rib extending to the downwardly extending portion, and increasing in depth as the said downwardly extending portion is approached. 5

9. In a roof plate, a body portion, a downwardly extending portion adjacent the front edge of the body, and a forwardly extending projection extending considerably beyond the downwardly extending portion, there being a transverse drainage groove adjacent the rear edge of the plate and on its upper surface and extending to the side edges, said drainage groove being adapted to be overlaid by the forwardly extending projection of an adjacent roof plate, and serving to obviate retention of moisture by capillary attraction between the overlapping portions of the plates. 15

10. In a roof covering structure, a series of sets of over-plates overlapping at the front and rear edges, each of said plates having side flanges, as well as a front downwardly extending portion transverse to the side flanges and joined to said side flanges, there being moisture guiding ribs on the lower surface of the plate for leading the collected moisture downwardly and to the side flanges, and a supporting trough disposed below the side flanges of adjacent sets of plates. 20 25 30

JOHANNES C. P. LEEMHUIS. 35
